UNITED STATES PATENT OFFICE.

WILHELM MUNDT, OF NEW YORK, N. Y., ASSIGNOR TO HIMSELF, RICKA COHN, AND JOSEPH HABERMAN, OF SAME PLACE.

COMBINED SPOOL-HOLDER AND STOP-MOTION FOR BRAIDING-MACHINES.

SPECIFICATION forming part of Letters Patent No. 469,974, dated March 1, 1892.

Application filed October 7, 1891. Serial No. 408,008. (No model.)

To all whom it may concern:

Be it known that I, WILHELM MUNDT, a citizen of the United States, and a resident of the city of New York, in the county of New

5 York, in the State of New York, have invented certain new and useful Improvements in a Combined Spool-Holder and Stop-Motion for Braiding-Machines, of which the following is a specification.

10 The object of my invention is to provide a new and improved combined spool-holder and stop-motion device for that class of braiding-machines known as the "Hercules Braiding-Machines," and in which a series of fixed 15 spool-holders are provided, around which movable spool-holders travel in serpentine slots.

The invention consists in the combination, 20 with a movable spool-holder, of a winged hub mounted to move vertically on the spool-holder, means for holding said winged hub in raised position, a fixed spool-holder provided with a sliding plate having wings adapted to trip and turn said hub to permit 25 it to drop, a ring on the frame-plate of the braiding-machine, which ring is provided with pins on which the lugs of the hub can act, and a stopping and starting gear operated from said ring.

30 The invention also consists in the construction and combination of parts and details, which will be fully described hereinafter, and finally pointed out in the claims.

In the accompanying drawings, Figure 1 is 35 an elevation of the fixed and movable spool-holder, parts being broken out and others being in section. Fig. 1^a is a face view of part of the standard. Fig. 2 is a vertical transverse sectional view of the movable spool-holder shown in Fig. 1. Fig. 3 is a sectional plan view on the line 3 3 of Fig. 1. Fig. 4 is a top view of the sliding stop-motion hub. Fig. 5 is a vertical longitudinal section of the same. Fig. 6 is a vertical longitudinal sectional view of the fixed spool. Fig. 6^a is a detail view of the tension-eyes and their support. Fig. 7 is a plan view of the base-plate of the braiding-machine, parts being in section. Fig. 8 is a vertical transverse sectional 40 view on the line 8 8 of Fig. 7. Fig. 9 is a de-

tail vertical sectional view on the line 9 9 of Fig. 8.

Similar letters of reference indicate corresponding parts.

The top plate A of the braiding-machine is 55 provided with a circular row of apertures A', in which the fixed spool-holders are fastened, said apertures A' being surrounded by the serpentine slot or track A². A ring A is arranged along the edge of the circular base-plate A, and is suitably guided by lugs B', 60 and is provided on its inner surface with a series of pins B² and with a cam-plate C. A handle C' projects from the outer surface of said ring, and is to be used for shifting the 65 same. A lever D is pivoted on the standard D' on the base-plate A³ of the machine, and is provided at one end with a fork D³, 70 embracing a collar E' of the vertically-movable member of clutch E on the driving-shaft E², which clutch when raised throws the machine out of gear with the driving-shaft and when lowered throws it in gear. A spring D², secured to the base-plate A³, presses the 75 forked end of the lever D upward, and thus has a tendency to press the other end downward, which other end is provided with an upwardly-projecting rod F, provided at its upper end with a laterally-projecting pin F', that is 80 adapted to rest upon the top edge of the cam-plate C. All these parts are old and well known, and are used in the braiding-machines.

The traveling spool-holders consist of the angular spindle G, on which the angular sleeve G' is mounted to slide, said sleeve being pressed upward by the helical spring G², surrounding the spindle and arranged between the lower end of the sleeve G' and the base-piece G³ of said spindle, which base-piece is 90 flanged and travels in the slots A² in the usual manner.

At the upper end of the sleeve G' the hub H is mounted on the spindle and is provided with two laterally-projecting beveled lugs H', 95 each having a pin H² on its upper surface, said hub being provided with a circular recess I, projecting down to about one-half the depth of the same, and in the bottom of said recess an aperture I' is formed in the hub, which 100

aperture I' has the same cross-section as the sleeve G', but is made larger to adapt the upper end of said sleeve to pass into the same. The spool J rests upon the adjustable collar 5 K, being provided with a neck K', projecting from its under side and into the circular recess I of the hub H.

The movable spool-holder is provided with the usual thread-guide and tension device 10 that are old and well known and need not be described here.

The fixed spool-holder consists of a standard L, provided with two brackets L', in which the spindle M is mounted, that passes through 15 the spool O. The standard L is provided with the eyes a and b, arranged a greater or less distance from each other, and between the same a series of eyes d are arranged on a serpentine line on said standard. A slide-plate 20 N, provided with the wings N', is mounted on the standard L and is provided with the upwardly-projecting wing N², having an aperture through which the thread can pass. The spool O is provided at the top and bottom 25 with the grooved flange O'.

P is a spring-wire secured to the bracket L' and having its free end resting in the groove of the top flange of the spool, so as to act as a drag or brake to prevent the spool from rotating too rapidly and the thread from unwinding 30 too rapidly.

The thread m upon the spool O is passed through the bottom aperture a of the standard L and through the aperture in the wing 35 N² of the slide-plate N and through the upper aperture b of the standard L, and thus as long as the thread is not broken the slide-plate N is held raised, as shown in Fig. 1, above the lugs H' of the hub H. Accordingly, as more or less tension is required for 40 the thread m, it can be passed through one or more of the eyes d, which are arranged in a zigzag line, as shown in Fig. 6.

The operation is as follows: When the machine is in operation, the clutch is lowered 45 and the pin F' of the rod F rests upon the top edge of the cam-piece C and the movable spool-holders travel in the serpentine tracks or slots A² around the fixed spool-holders. The hub H is in a raised position and rests 50 upon the upper edge of the sleeve G', said hub standing at an angle of ninety degrees to the sleeve G'—that is to say, each diagonal axis of the hub H is at right angles to the corresponding diagonal axis of the sleeve G'. The pins H² on the upper end of the hub bear 55 against the under side of the collar K, the neck K' of which is within the circular recess I of the hub. In case a thread on a fixed

60 spool breaks, the corresponding plate N drops until it rests upon the bottom bracket L', and as its projecting wings N' are in the track of the lugs H' of the several movable spools the lug H' of the first movable spool, arriving at 65 the fixed spool, at which the plate N' has dropped, strikes against one of the wings of

the plate N, whereby the hub is turned axially ninety degrees, so that the sides of its angular aperture I' are now in line with the sides of the sleeve G', and in consequence 70 thereof the hub H drops to the bottom of the spindle G and rests on the base G³ of the same, as shown in dotted lines in Fig. 1, and when it arrives at one of the pins B² of the ring B on the plate A it strikes against such 75 pin B² and moves the ring B in the direction of the arrow X', Fig. 7. Thereby the cam-piece C is shifted from under the pin F' of the rod F of the lever D, permitting the spring D² of said lever D to throw upward the forked 80 end of said lever, whereby the clutch is shifted in such a manner as to disengage the operating mechanism of the machine from the driving-shaft, and thus the machine is stopped. After the broken thread has been tied and drawn 85 up to raise the slide-plate N, the hub H is raised to the top of the sleeve G and then is turned ninety degrees, when the machine is again started by shifting the ring B in the inverse direction of the arrow X', whereby the top 90 edge of the cam-piece C acts on the pin F' of the rod F and raises the corresponding end of the lever D, whereby the forked end of the lever D is lowered and the clutch brought in gear with the driving-shaft, and thus the machine begins to operate. 95

Having thus described my invention, I claim as new and desire to secure by Letters Patent—

1. The combination, with a series of fixed 100 spool-holders, of a sliding plate, each of said sliding plates having wings and eyes, a movable spool-holder, a sliding hub on the same, which hub is provided with projections, a ring provided with projections on which the 105 projections of the hub can act, and a stopping and starting gear acted upon by said ring, substantially as set forth.

2. The combination, with a fixed spool-holder, of a sliding plate on the same provided 110 with wings and an eye, a movable spool-holder, a sliding hub on the same, a ring provided with projections on which the hub can act, and a stopping and starting gear acted upon by said ring, substantially as set forth. 115

3. The combination, with a movable spool-holder having an angular part, of a sliding angular sleeve on said angular part, a hub resting on said sleeve and provided with an angular aperture, into which said sleeve can 120 pass, lugs on said hub, and a fixed spool-holder provided with a sliding plate adapted to trip and turn said hub, substantially as set forth.

4. The combination, with a movable spool-holder having an angular part, of a sliding sleeve mounted to slide on said angular part, a spring for pressing said sleeve upward, a hub provided with lugs and with an angular aperture adapted to receive said sleeve, said 130 hub being mounted on the spool-holder spindle above the sleeve, so as to turn on said

spindle, and a fixed spool-holder provided with a movable plate having wings adapted to trip and turn said hub, a ring having projections on which the lugs of the hub can act, and a stopping and starting gear acted upon by said ring, substantially as set forth.

In testimony that I claim the foregoing as

my invention I have signed my name in presence of two subscribing witnesses.

WILHELM MUNDT.
